(57) **CLAIM**

The ornamental design for a unified passenger service unit, as shown and described.

DESCRIPTION

FIG. 1 is a perspective view of a unified passenger service unit in a passenger seating environment; FIG. 2 is an enlarged perspective view of the unified passenger service unit of FIG. 1 with the environment shown in that view removed; FIG. 3 is a right side elevation view of the unified passenger service unit of FIG. 2; FIG. 4 is a left side elevation view of the unified passenger service unit of FIG. 2; FIG. 5 is a top plan view of the unified passenger service unit of FIG. 2; FIG. 6 is a bottom plan view of the unified passenger service unit of FIG. 2; FIG. 7 is a front elevation view of the unified passenger service unit of FIG. 2; and, FIG. 8 is a rear elevation view of the unified passenger service unit of FIG. 2. The broken lines in FIGS. 1, 2, and 7 illustrate portions of the invention and environment that form no part of the claimed design. The dash-dot-dash broken lines are used to enclose the environment in FIG. 1 and form no part of the claimed design.
